UNITED STATES PATENT OFFICE

BERT E. MILLS, OF OAK PARK, ILLINOIS, ASSIGNOR TO MILLS NOVELTY COMPANY, OF CHICAGO, ILLINOIS, A CORPORATION OF ILLINOIS

DESIGN FOR A CLOCK CASE

Application filed December 18, 1931. Serial No. 42,129. Term of patent 3½ years.

To all whom it may concern:

Be it known that I, BERT E. MILLS, a citizen of the United States, and a resident of Oak Park, in the county of Cook and State of Illinois, have invented a new, original, and ornamental Design for a Clock Case, of which the following is a specification, reference being had to the accompanying drawings, forming a part thereof.

Fig. 1 is a front elevational view of a clock case showing my new design; and Fig. 2 is a side elevational view of the same.

I claim:

The ornamental design for a clock case as shown.

BERT E. MILLS.
